UNITED STATES PATENT OFFICE

CARL KREMP, OF PHILADELPHIA, PENNSYLVANIA, ASSIGNOR TO H. A. WEYMANN & SON, INC., OF PHILADELPHIA, PENNSYLVANIA, A CORPORATION OF PENNSYLVANIA

BANJO

Application filed November 23, 1927. Serial No. 235,178.

My invention relates to new and useful improvements in a banjo and has for its primary object to construct a musical instrument of the banjo type wherein a resonator or amplifier is combined as a part of the instrument in a unitary structure.

Another object of the invention is to provide a musical instrument of the banjo type including a straining ring or hoop which is held in place by the usual straining hooks and their associated nuts, said hooks passing through an enlarged portion of the instrument rim and a resonator or amplifier mounted on the rim, and having apertures therein for the passage of the nuts and for the insertion of a wrench to adjust said nuts.

A further object of this invention is to so construct the body of the musical instrument as to eliminate the usual protruding brackets and to permanently mount on said instrument an amplifier or resonator whereby the musical tones emanating from the instrument will be confined in a relatively small area and permitted to pass therefrom toward the audience when faced by the musician, thus giving a greater scope to said tones so that they may be heard at a considerable distance and at the same time modifying the musical vibrations to give mellowness thereto, said resonator or amplifier being provided with apertures in its rear or end wall for access to nuts on straining hooks which pass through an enlargement of the instrument body or rim so that the body, as a whole, presents a smooth surface and eliminates all protuberances that might catch in a snare the clothing of the musician.

Another object of the invention is to provide a musical instrument, comprising, in combination, an instrument body or rim having an enlargement for the reception of the straining hooks, an amplifier fixed to the back or rear edge of the rim, and provided with apertures for access to nuts on the straining hooks, the sides of said amplifier being spaced from the rim which space is in communication with the interior of the rim through holes in the rear edge of the latter and an apertured flange mounted on the shoulder formed by the enlargement of the

rim, and extending toward, and preferably out of contact with the side wall of the amplifier so as to substantially conceal the space between the banjo rim and amplifier from the view of an audience.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:

Fig. 1, is a face view of a banjo constructed in accordance with my invention.

Fig. 2, is an enlarged sectional view thereof on the center line of the instrument neck, a portion of the latter being left in elevation.

Fig. 3, is an enlarged fragmentary face view of the instrument to illustrate details of construction.

Fig. 4, is a similar view of the back of the instrument.

Fig. 5, is a section on the line 5—5 of Fig. 2.

In carrying out my invention as herein embodied, 6 represents the rim of the musical instrument constructed of any suitable material, preferably wood and made from one or more pieces as is well known in the manufacture of musical instruments. This rim has an enlargement or off-set portion 7 providing a shoulder 8 and across that portion of smaller exterior diameter, is disposed the parchment head 9, and if found desirable, a metal ring 10 may be placed about the smaller portion of the rim with an inturned roll flange overlying the edge of the rim and on which the parchment head rests.

The parchment head is held in place by a straining ring or hoop 11 engaged by the hooked ends of the straining hooks 12 which pass through the bores 13 in the enlarged or off-set portion of the rim and project into the counter bores 14 communicating with the aforementioned bores. Nuts 15 are threaded on the straining hooks entirely within the counter bores, it being understood that the straining hooks are of such length that their

100

threaded ends will not protrude from the counter bores when the straining ring is adjusted to its full extent.

On the rear edge of the instrument rim is mounted an amplifier or resonator 16 including a back or end wall 17, larger in size than the body or rim of the instrument and preferably concavo-convex. From the outer edge of the back extends the side wall 18 of a height substantially equal to that of the enlarged portion of the banjo rim and spaced from said rim to provide a sound channel 19 in communication with the interior of the rim through holes 20 formed in said rim adjacent the rear or inner edge thereof. As before stated, the resonator or amplifier includes the back 17 and the side wall 18 and is fixed to the rear edge of the instrument rim by a suitable adhesive or otherwise and in order to have access to the nuts 15, the back of the amplifier is provided with apertures 21 which register with the counter bores 14 and in fact, form extensions of said counter bores.

In order to cover up the sound channel 19, and practically make it invisible, a removable flange 22 of any desired configuration and ornamentation is mounted upon the shoulder 8 and held thereon by screws 23 or equivalent fastening means, and said removable flange extends from the outer circumference of the smaller portion of the instrument rim toward but preferably spaced from the side wall 18 of the amplifier. While, as stated, I prefer to terminate the outer edge of the removable flange short of the side wall of the amplifier, yet it could extend into a groove or over the outer edge of the amplifier side wall, since its only function is to conceal the channel. The removable flange has openings 24 through it in the region of the sound channel to provide for the issuance of the sound waves after they have passed into the channel from the interior of the instrument through the holes 20.

From the foregoing description, it will be obvious that a musical instrument construction in accordance with the above description will combine the advantages of a smooth surface musical instrument and an amplifier or resonator without the disadvantages of having to remove the amplifier when it is necessary or desirable to regulate the parchment head through the medium of the fillister screws.

The side wall of the amplifier is preferably cut out for the neck 25 of the instrument, although it is to be understood that said side wall could be fitted into a groove in said neck.

Of course I do not wish to be limited to the exact details of construction as herein shown, as these may be varied within the limits of the appended claims without departing from the spirit of my invention.

Having thus fully described my invention, what I claim as new and useful is:

1. A stringed musical instrument including a rim, an amplifier fixed to the rear edge of said rim with the side wall thereof in spaced relation to said rim to form a sound channel, said sound channel being in communication with the interior of the rim through holes in the latter, straining hooks adapted to engage a straining ring on the instrument and passing through bores and into counter bores in the rim, and nuts having threaded engagement with the straining hooks and setting within the counter bores to which access is had through apertures in the amplifier. 70 75 80

2. In a device of the character stated, a banjo including a rim having an enlarged portion at its rear in which are formed bores and counter bores and further provided with radial holes at the rear edge thereof, and an amplifier fixed to the rear of the rim and provided with holes for registration with the counter bores. 85

3. A banjo including a rim, an amplifier fixed to the rear edge of said rim and combined therewith in a unitary structure, and said amplifier having apertures in the back registering with bores edgewise through the rim, each rim bore being of two different diameters to receive a straining hook and its nut, to the latter of which access is had through an aperture in the amplifier. 90 95

4. In a banjo, a rim having an enlarged rear portion extending outside of the forward portion and providing a shoulder, a parchment head disposed across the forward end, a straining ring for engagement with said head, straining hooks coacting with the straining ring and passing through bores in the enlarged portion of the rim and projecting into counter bores, communicating with said bores, nuts threaded on said straining hooks and located within the counter bores, an amplifier including a back and side wall partially enclosing the rim and fixed thereto through the medium of the back wall with the side wall spaced from over the rim to form a sound channel in communication with the interior of the rim through radial holes formed in said rim at the rear edge thereof, the back of said amplifier having apertures aligned with the counter bores to permit access to the nuts. 100 105 110 115

5. The structure set forth in claim 4 in combination with an apertured removable flange mounted on the enlarged portion of the rim and projecting across the outer end of the sound channel. 120

6. In a stringed musical instrument, a rim having a peripheral enlargement about the lower portion to produce a shoulder, said rim having apertures adjacent its lower edge, an amplifier disposed across the lower edge of the rim and surrounding the enlargement 125 130 135

in spaced relation thereto, and means mounted upon the shoulder to partially cover the space between said rim and amplifier.

7. In a stringed musical instrument, a rim, an amplifier including a back wall secured to the back edge of said rim with the edges of said back wall projecting beyond the outer face of the rim, an annular member secured to the projecting edge of said back wall and surrounding the rim in spaced relation thereto to provide a sound chamber in communication with the interior of the rim through apertures in the latter, a head disposed only over the front edge of the rim and tensioning means for said head, said tensioning means including straining hooks passing through the rim.

8. A banjo and amplifier combined in a unitary structure, said banjo including a rim, a head disposed across the front thereof, a straining hoop coacting with the head, straining hooks engaging the hoop and passing part-way through the rim, nuts threaded on said hooks and said amplifier including a back wall permanently fixed to the back of the rim and having holes therethrough for access to the nuts and a side wall projecting from the back wall and spaced from the outer side surface of the rim to provide a sound channel in communication with the interior of the rim through holes in the latter.

9. A banjo and an amplifier combined therewith in a unitary structure, said banjo including a rim having holes therethrough from face to face and further provided with bores and counter-bores for the reception of straining hooks, said amplifier including a back and a side wall spaced from the banjo rim to form a sound channel in communication with the interior of the banjo rim through the holes in the latter and the back of said amplifier having apertures therein communicating with the counter-bores.

In testimony whereof, I have hereunto affixed my signature.

CARL KREMP.
